UNITED STATES PATENT OFFICE.

STANLEY MACOMBER, OF MASSILLON, OHIO, ASSIGNOR TO THE MACOMBER STEEL COMPANY, OF CANTON, OHIO, A CORPORATION OF OHIO.

BANK-VAULT REINFORCING.

Application filed September 21, 1925. Serial No. 57,610.

In the building of bank vaults, the practice is to make the walls, floor and roof of solid concrete usually from a foot and a half to two feet thick, setting in at the door opening a heavy steel frame and door. Insurance ratings and government specifications further require that the type of reenforcing steel used in reenforcing the concrete portion of the vault be such as to prevent entry by any means whatsoever. These specifications entail the placing of a considerable quantity of steel which at present is handled in separate bars or pieces, so that not only is the installation of such reenforcing material an expensive operation, but also its placement has to be carefully supervised in order to insure its effectiveness as a protection.

The object of the present invention is to provide an arrangement of steel reenforcing material for bank vaults and the like which will permit of the preliminary assembly of such material in a relatively inexpensive manner and which will at the same time facilitate and insure the correct placement of such material in the course of erection of the vault.

To the accomplishment of the foregoing and related ends, the invention, then consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

In said annexed drawing:

Fig. 1 is a broken perspective view of a vault wall showing the manner in which my improved reenforcing material is incorporated therein; Fig. 2 is a side elevation and Fig. 3 an end elevation of one of the units or frames into which such material is preliminarily assembled; and Fig. 4 is a transverse section of several of such frames as they will be disposed in the wall, the plane of the section being indicated by the line 4-4, Fig. 2.

The material out of which the reenforcing units are fabricated is steel bars which may be round rods, as shown, or of any desired shape and cross-section. Prior to incorporating such bars in the wall, floor or roof

of the vault, they are reversely bent to form a succession of oppositely directed V's and the bars thus formed are then placed side by side in the wall, etc., with the points or curves that mark the successive bends therein directed towards the outside and inside of the wall, respectively. The bars are furthermore placed so that such points or curves of adjacent bars are staggered. It will accordingly be seen that by placing bars of this form sufficiently close together, a type of reinforcement is provided that approaches the ideal since in cutting or burning a hole at any point through the wall, it becomes necessary to work endwise at all times against a large number of inclined sections of these bars.

To expedite the installation of the reenforcing material and reduce its cost in the field, the reversely bent bars as described are desirably assembled into frames. In the form illustrated (see Figs. 2 and 3) two parallel bars 1, of relatively large diameter, constitute the edges of the frame. These bars may be of any desired length within the limiting dimensions of the particular section of wall in which the reenforcing material is to be incorporated and will similarly be placed apart a distance somewhat less than the thickness of such wall so as to permit the material to be wholly incorporated within the sides of the latter, as illustrated in Fig. 1. Reversely bent web bars 2 of the sort described above are then welded to the respective sides of said parallel bars 1, said web bars being of the same or slightly less diameter in cross section and being placed with the bends 2^a therein in staggered relation so that the inclined portions of each bar will cross at points approximately midway between the parallel bars 1. The interior space lying between the web bars 2, which space is as wide as the diameter of the parallel bars, is then filled with other reversely bent web bars 3. Two such intermediate bars are shown as thus enclosed within the main elements of the structure (see Fig. 4) but the number of these bars 3 will of course vary, depending upon their diameter and the width of the space in question. Said bars 3, like the outside web bars 2, are preferably disposed so that the inclined portions thereof cross at approximately the mid-point of the space between the parallel bars 1. Inasmuch as these bars 3 are thus confined not only laterally by the

105
110
115

outside web bars 2, but also by having the bends therein abut against the parallel bars 1, it is not necessary to weld them except at their ends or at the most at a few intermediate points.

In placing the frames constructed as aforesaid in the position they are to occupy in the finished wall, they are disposed side, by side as shown in Figs. 1 and 4, and a result when approached from either side of the wall, it will be evident that the reenforcement will present first of all an aligned series of the parallel edge bars 1 and within these a maze composed of the inclined sections of the lateral web bars 2 and the intermediate web bars 3, the angles between such inclined sections in every case being presented outwardly. The web bars 2 being firmly welded or otherwise secured to the parallel bars, each frame forms a truss-like structure capable of acting as a mechanical reenforcement for the wall as well as a protective reenforcement. Despite the close assembly of the frames, the several component bars are nevertheless at all times held in proper spaced relation so as to permit concrete to be freely flowed not only into the interior portions of the frame, but also around their edges, and thus insure at all points a proper bond between such concrete and the reenforcing rods.

From the standpoint of manufacture, the only mechanical operations involved are the bending of the web bars and the subsequent welding of them together in the manner previously described. These operations are relatively simple and easily performed and as a result, the manufacturing cost over and above the cost of the material may be kept at a minimum.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

50 1. A protective reenforced-concrete bank-vault wall comprising, masonry presenting exterior and interior wall faces, and a plurality of massed side-by-side parallel reenforcement frames transversely embedded in said masonry, each frame comprising longitudinal bars and a plurality of reversely-bent tie-bars secured at their angles to said longitudinal bars, whereby the piercing of the wall is barred not only by the masonry and the longitudinal bars, but also by the constantly-presented broken ends of the inclined transverse tie-bars.

65 2. A protective reenforced-concrete bank-vault wall comprising, masonry having exterior and interior wall faces, and a plural-

ity of parallel reenforcement frames embedded in said masonry, each frame comprising parallel longitudinal bars and a plurality of side-by-side transverse reversely-bent tie-bars secured at their angles to said longitudinal bars, the bends of said transverse bars being staggered, and other inclined transverse tie-bars held in the space between said longitudinal bars and said first-named inclined bars, whereby the piercing of the wall is barred not only by the masonry and the longitudinal frame bars, but also by the constantly-presented broken ends of the two sets of inclined transverse tie-bars.

3. In a protective reenforcing unit for concrete bank-vault walls and the like, the combination of parallel edge bars; two reversely bent web-bars permanently attached at their bends to opposite sides of said edge bars; and additional web-bars held in the space between said edge bars and said first-named web-bars.

4. In a protective reenforcing unit for concrete bank-vault walls and the like, the combination of parallel edge bars; two reversely bent web-bars permanently attached at their bends to opposite sides of said edge bars, the bends of said bars being staggered with respect to each other; and additional web-bars held in the space between said edge bars and said first-named web-bars.

5. In a protective reenforcing unit for concrete bank-vault walls and the like, the combination of parallel edge bars; two reversely bent web-bars permanently attached at their bends to opposite sides of said edge bars; and additional web-bars held in the space between said edge bars and said first-named web-bars, the bends of the latter as well as those of said interior web-bars being staggered with respect to each other.

6. In a protective reenforcing unit for concrete bank-vault walls and the like, the combination of edge bars; reversely bent web-bars permanently attached at their bends to the sides of said edge bars; and additional reversely bent web bars laterally confined by the first-named web-bars and having their angles interiorly abutting the edge bars and being permanently attached at widely scattered points to the other web-bars and said edge bars.

7. In a protective reenforcing unit for concrete bank-vault walls and the like, the combination of longitudinal edge bars; and a plurality of side-by-side transverse reversely bent web-bars secured to said edge bars, the angles of the outside web-bars lying adjacent the sides of said edge bars, and the intermediate web-bars being equal in aggregate thickness to said edge bars.

8. In a protective reenforcing unit for concrete bank-vault walls and the like, the combination of longitudinal edge bars; and

a plurality of side-by-side transverse reversely bent web-bars secured to said edge bars, the angles of the several web-bars lying adjacent said edge bars in rotation, the angles of the outside web-bars lying adjacent the sides of said edge bars, and the intermediate web-bars being equal in aggregate thickness to said edge bars.

9. A protective reenforced-concrete bank-
10 vault wall comprising, masonry presenting exterior and interior wall faces, and a plurality of massed side-by-side parallel reen-

forcement frames transversely embedded in said masonry, each frame comprising longitudinal bars and a plurality of side-by-side 15 transverse reversely bent web-bars secured to said longitudinal bars, the transverse bars of each frame being equal in aggregate thickness to the space between adjacent longitudinal bars plus the thickness of a longitudinal bar. 20

Signed by me this 18 day of Sept., 1925.

STANLEY MACOMBER.

CERTIFICATE OF CORRECTION.

Patent No. 1,669,988.

Granted May 15, 1928, to

STANLEY MACOMBER.

It is hereby certified that error appears in the printed specification of the above numbered patent requiring correction as follows: Page 2, line 18, after the word "outwardly" insert the paragraph:

"Therefore, an attempt to pierce the wall would be barred both by the masonry and the longitudinal frame members 1, and also, after the angles of the inclined transverse tie-bars are broken, by the rigidly secured broken ends of said tie-bars, which broken ends would be continuously presented throughout the thickness of the wall and offer constantly a bar to the piercing of the same.";

and that the said Letters Patent should be read with this correction therein that the same may conform to the record of the case in the Patent Office.

Signed and sealed this 12th day of June, A. D. 1928.

M. J. Moore,
Acting Commissioner of Patents.
